UNITED STATES PATENT OFFICE.

ADAM ROSENKRANZ, OF ALLEGHENY, PENNSYLVANIA.

OIL-WELL PUMP.

SPECIFICATION forming part of Letters Patent No. 530,350, dated December 4, 1894.

Application filed August 22, 1893. Serial No. 483,736. (No model.)

To all whom it may concern:

Be it known that I, ADAM ROSENKRANZ, of Allegheny, in the county of Allegheny and State of Pennsylvania, have invented a new and Improved Oil-Well Pump, of which the following is a full, clear, and exact description.

The object of the invention is to provide a new and improved pump, which is simple and durable in construction, very effective in operation, and more especially designed for use in oil and other wells, and arranged to prevent grit or other impurities, from passing between the plunger and the parts in which it works, to prevent injury to the plunger.

The invention consists of certain parts and details and combinations of the same, as will be hereinafter described and then pointed out in the claim.

Reference is to be had to the accompanying drawings, forming a part of this specification, in which similar letters of reference indicate corresponding parts in all the views.

Figure 1 is a sectional side elevation of the pump. Fig. 2 is an enlarged sectional side elevation of the plunger on the line 2-2 in Fig. 1. Fig. 3 is an enlarged sectional plan view of the improvement on the line 3-3 of Fig. 1; and Fig. 4 is an enlarged sectional side elevation of the suction end of the pump casing, on the line 4-4 in Fig. 1.

As illustrated in Fig. 1, the pump is arranged in the oil well casing A, into which extends the tubing B, supporting at its lower end the pump casing C, comprising a barrel D attached at its upper end to a stuffing box D' connected by a cylinder D² with a stuffing box D³ screwed on the lower end of the tubing B. The barrel D and cylinder D² are somewhat less in diameter than the oil well casing A, while the stuffing boxes D' and D³ fit snugly in the said casing, as shown. On the lower end of the barrel D is secured a cap E, carrying the perforated suction pipe F extending into the liquid to be pumped out of the oil well casing A, as plainly shown in Fig. 1.

In the cap E is arranged a valve casing G' containing a ball valve G, through which the oil can pass into the barrel D; and on the upper end of the said casing G' is arranged

a threaded boss G² adapted to be engaged by the threaded lower end H' of the plunger H, made hollow, and extending into the barrel D and through the stuffing boxes D', D³ and cylinder D², up into the tubing B to connect at its upper end with the usual sucker rod B' operated from the ground in the usual manner. In the lower end of the hollow plunger rod H is arranged an inlet valve H² and at the upper end of the said plunger rod is arranged a discharge valve H³, both valves being preferably of the ball construction, as plainly shown in the drawings.

In the cylinder D² are arranged two sets of packing I and I', preferably made of hemp or other suitable material, coiled around the plunger rod H so as to pack the same. The packing I rests with its lower end on the somewhat inclined bottom of the stuffing box D' and is pressed on, on top, by a collar I² through which passes loosely the plunger rod H. The collar I² is provided with a shoulder formed by a central inward projection or sleeve I⁴. The other packing I' rests with its upper end on the under curved surface of the top stuffing box D³, and the lower end of the said packing I' is engaged by a collar I³, similar in construction to the collar I² for the packing I. Between the two collars I² and I³ a coil spring J is interposed, which at its ends encircles the projections I⁴ of the collars, and serves to press the collar I³ upward and the collar I² downward, so as to firmly force the packings in contact with the plunger rod H and against their corresponding stuffing boxes D³ and D'. The plunger H is made tapering at its lower end, so that it can be readily withdrawn and re-inserted without removing the pump barrel.

The stuffing box D³ is provided with an upwardly flaring bore, to permit of readily inserting the plunger.

When the several parts are in the position illustrated in Fig. 1 and a reciprocating motion is given to the plunger rod H, in the usual manner, by working the sucker rod B', then the liquor in the lower end of the oil well casing A is drawn into the suction pipe F and passes to the valve casing G' and valve G, into the barrel D, on each up-stroke of the said plunger rod. On the down-stroke of the said plunger rod H, the valve G closes

and the valve H^2 opens, so that the liquor in the barrel D passes into the hollow plunger rod H, to be discharged at the upper end thereof by the valve H^3 opening into the tubing B. Now, it will be seen that the liquor in the barrel D is transferred to the tubing B without passing through the packing cylinder D², and grit or other impurities are prevented from entering the said packing cylinder, either from above or below, as the stuffing boxes D' and D³ and the plunger rod H are well packed. It is understood that on the up-stroke of the plunger rod H, the valves H^2 and H^3 close, so that the liquor is drawn into the barrel D, as above described.

As no grit can pass between the plunger and the bearing surfaces thereof, the wear of the said plunger is reduced to a minimum and consequently the pump is not liable to easily get out of order.

The valve casing G' may be removed for cleaning or repairing it, by bringing the plunger H down to an engagement with the

boss G², then turning the plunger to screw it down on the said boss, and thereupon with drawing the plunger with the valve casing.

Having thus described my invention, I claim as new and desire to secure by Letters Patent—

The combination, with the pump barrel, the packing cylinder located at one end thereof, and the plunger adapted to reciprocate in the said barrel and packing cylinder, of a stuffing box located at each end of the packing cylinder and adapted to engage the plunger, said stuffing boxes projecting outwardly beyond the packing cylinder to engage the pump casing, a packing held in the said cylinder at each end thereof, and a spring coiled in the cylinder and arranged between the said packings to press them into contact with the plunger, substantially as described.

ADAM ROSENKRANZ.
